UNITED STATES PATENT OFFICE.

PAHR ANDERSON, OF CAMBRIDGE, MASSACHUSETTS, ASSIGNEE TO DOVER STAMPING & MANUFACTURING COMPANY, OF PORTLAND, MAINE, A CORPORATION OF MAINE.

POUR-OUT.

1,164,775.

Specification of Letters Patent. Patented Dec. 21, 1915.

Application filed October 28, 1912. Serial No. 723,633.

To all whom it may concern:

Be it known that I, PAHR ANDERSON, of Cambridge, in the county of Middlesex and State of Massachusetts; a citizen of the United States, have invented a new and useful Improvement in Pour-Outs, of which the following is a specification.

My invention relates to cans which are especially adapted to hold gasoline, naphtha and other volatile liquids and comprises a valve which may be easily opened in the act of pouring out the contents of the can. For liquids which volatilize easily, especially such as give off an inflammable or explosive vapor, it is desirable that the can be closed at all times except during the pouring operation, and one feature of my invention relates to the use of a lever for opening the valve, which lever is so located as to be conveniently operated in the act of pouring from the can.

My invention in its preferred form is shown in the drawings applied to cans of different sizes.

Figure 1 shows in vertical section a portion of a comparatively large can to which my invention is applied, Fig. 2 being a plan or top view thereof. Fig. 3 is a sectional detail of a small can to which my invention is applied, Fig. 4 being a top view thereof.

In each view A is the can which in general is of any ordinary construction. Projecting inward from its top is a perforated tube or cage B closed at the bottom and having a collar b¹ at its top, the lower edge of which is suitably shaped to form a valve seat. This tube forms a cage in which is the valve C, the valve being held normally against its seat by a spring D which rests on the bottom b of the tube and is of sufficient length and strength to press the valve against its seat under all ordinary conditions. I have shown in the drawings a spherical valve and its appropriate seat as such a valve has proved satisfactory for the present purpose, but I do not mean to limit my invention to that type of valve nor to the use of a collar to provide a valve seat.

E is the spout of the pour-out and as shown it is somewhat cup or funnel shaped and is narrowed at one end to form a nozzle E¹ to guide the liquid which is being poured.

In Figs. 3 and 4 the nozzle is provided with a cover E² partly cut away to form an outlet for the liquid. I have shown the

pour-out as funnel shaped so that it may be useful in filling the can. I also prefer to use the spout as the fulcrum for the lever F which is attached thereto either by perforating the walls of the pour-out and passing the end of the lever therethrough and upsetting the ends as shown at f (Figs. 1 and 2) or else by binding either end around an eye e made, for example, of wire and soldered to the inside of the spout as shown in Figs. 3 and 4.

The valve C has a rod c which projects upward and terminates in a ring c¹ and in the preferred form of my invention shown, the lever F is made of a piece of wire bent into the form of a loop f¹ the ends of which are attached to the spout as described above, the intermediate portions passing through the ring c¹ as shown in each view.

In a smaller can, say one quart, such as is shown in Figs. 3 and 4, which is provided with a handle G by which it is held and tipped for pouring, the loop f¹ may be brought near the handle G as shown so that when one tips the can to pour from it, he depresses the lever F by pressing the thumb of his lifting hand on the loop f¹ and this depresses the valve rod c and opens the valve C, allowing the liquid to flow out.

Figs. 1 and 2 show my invention applied to a large can, say one of five gallons, which requires both hands to lift it. In this can a bail H is provided suitably hinged as at h to projections h¹ from the top of the can and bent as at h² so that the bent portion rests on the loop f¹ of the lever. The can is also provided with the usual loop or handle H¹ near the bottom of the can to assist in lifting it. In this case the can is lifted by the bail H and to pour from it the user with his other hand grasps the loop H¹ and lifts the can into or toward a horizontal position. As the bail H remains in vertical position the can as it is tipped brings the lever F into engagement with the bail H so that the free end of the lever F is depressed and depresses the valve rod and so opens the valve.

It is not essential that either the lever F or the bail H shall be pivotally attached in the exact manner shown nor to the parts of the can shown so long as they are so attached as to perform the functions described. The cage or tube B may be otherwise constructed if thought best. As shown it provides a support for the spring, a guide for the valve

and an ample passage for the liquid during the pouring operation. The tube may be perforated as shown or otherwise constructed to provide for the free passage of liquid therethrough, and form a cage for the valve.

What I claim as my invention is:—

1. A can having an opening adapted to serve as an inlet for filling said can and also 10 as a pour-out, a cage suspended from said opening, a valve located in said cage and adapted normally to keep said opening in a closed position, and means for opening said valve comprising a rod extending upwardly 15 from said valve, a lever fastened to said can, extending over said rod and adapted to engage therewith and a bail hinged to said can and adapted to engage said lever when said can is in a pouring position and cause it to 20 operate said lever to open said valve.

2. A can having an opening adapted to serve as an inlet for filling said can and also as a pour-out, a valve normally closing said opening, means for holding said valve in

closed position and means for opening said 25 valve comprising a rod extending upwardly from said valve, a lever fastened to said can and extending over said rod and adapted to engage therewith, and a bail hinged to said can and adapted when said can is in pouring 30 position to engage said lever and cause it to operate said lever to open said valve.

3. A can having an opening adapted to serve as an inlet for filling said can and also 35 as a pour-out, a valve normally closing said opening, means for holding said valve in a closed position, and means for opening said valve comprising a lever fastened to said can, said lever being adapted to operatively engage said valve and a bail hinged to said can adapted when said can is in a pouring 40 position to engage said lever and cause it to open said valve.

PAHR ANDERSON.
